UNITED STATES PATENT OFFICE.

MATTHEW HOGAN, OF HARTFORD, CONNECTICUT, ASSIGNOR TO THE HARTFORD SANITARY PLUMBING COMPANY, OF SAME PLACE.

SELF-CLOSING COCK.

SPECIFICATION forming part of Letters Patent No. 232,350, dated September 21, 1880.

Application filed March 7, 1879.

To all whom it may concern:

Be it known that I, MATTHEW HOGAN, of Hartford, in the county of Hartford and State of Connecticut, have invented certain new and useful Improvements Pertaining to a Self-Closing Cock, of which the following is a specification, reference being had to the accompanying drawings, where—

Figure 1 is a side view of the cock with a part of the body or casing broken away. Fig. 2 is a view of the cock in central vertical longitudinal section. Fig. 3 is a view of the cock in cross-section on the plane denoted by the dotted line *x x*.

The letter *a* denotes the body or main casing of the cock. *b* denotes a tube screwing into the induction end of the same, provided with orifices *c*. *d* denotes a cap screwing upon the inner end of induction-tube *b*, provided with an orifice, *e*, for the passage of the valve-rod *f*. The orifice *e* is also a valve-opening.

The letter *g* denotes a conical thimble fitting into cap *d*, provided with orifice *h*. The letter *i* denotes a spider-legged plate fitting into the induction-tube *b*, the openings between the legs forming, when this plate is in place in the induction-tube, orifices which admit the water past this plate outside of the tubular rubber valve *j*, which at the rear end fits on a boss projecting from the plate *i* and at the front end fits on the thimble *g*. The letter *k* denotes a small water-way through plate *i*, the opening of which is enlarged or dimin-

ished at pleasure by means of the regulating-screw *l*.

The valve-rod *f* passes through the casing *a*, for manipulation on the outside thereof. It bears within the cap *d* the valve *m*, pressed to its seat by spring *n*. When the valve *m* is closed no water flows through the cock; but when it is opened the water passes through it more freely than it can come through the water-way *k*, the latter being the smaller of the two. This allows the water bearing on the outside of the tubular rubber valve *j* to press this tubular valve inward, uncovering the orifices *c*, allowing the water to flow freely through them and out at the induction end of the casing *a*. When the valve *m* closes, the water fills into the inside of tubular valve *j*, and expands it to its normal shape, covering and closing the orifices *c*, and shutting off the flow of water through the cock.

I claim as my invention—

1. The combination, in a water-cock, of the collapsing tubular valve *j* with the perforated casing or valve-seat *b*, all substantially as described, and for the purpose set forth.
2. The combination, in a water-cock, of the perforated casing or valve-seat *b*, the collapsing tubular valve *j*, the plate *i*, provided with water-way *k*, the cap *d*, and the valve *m*, all substantially as described, and for the purpose set forth.

Witnesses: MATTHEW HOGAN.
